UNITED STATES PATENT OFFICE.

ELLIS DRAKE, OF STOUGHTON, ASSIGNOR TO HIMSELF AND JOHN S. SMITH, OF LEICESTER, MASSACHUSETTS.

IMPROVEMENT IN COMBINED PERCUSSION AND TIME FUSES FOR SHELLS.

Specification forming part of Letters Patent No. 137,186, dated March 25, 1873.

To all whom it may concern:

Be it known that I, ELLIS DRAKE, of Stoughton, in the county of Norfolk and State of Massachusetts, have invented a new and useful Double Percussion, a Time, and a Time-Regulating Fuse for Elongated Shells or Projectiles; and I do hereby declare that the following is a full, clear, and exact description thereof, sufficient to enable others skilled in the art to which my invention appertains to make and use the same, reference being had to the accompanying drawing, in which—

Figure 1 is a perspective view of my improved double percussion, time, and time-regulating fuse. Fig. 2 is a longitudinal central section of the same. Fig. 3 is a detached view of the rear percussion-plunger. Fig. 4 is an end view of the fuse-case head and front percussion-plunger. Fig. 5 is a perspective view of a time-fuse.

In each figure similar letters indicate corresponding parts.

This invention consists of a fuse-case provided with longitudinal grooves for the reception of a plunger having spurs or legs to receive percussion-caps, in combination with a retaining-spring to hold the plunger in position until the proper time, when it will yield and permit the plunger to be thrown forward and explode the caps, all as will more fully hereinafter appear.

In the accompanying drawing, the letter A designates a fuse-case, which is made of any suitable form or construction, and of any desired metal best adapted for the purpose. The fuse-case is provided with the ordinary head B and with a screw portion, C, by which means the case is screwed into the shell or projectile. The fuse-case is formed hollow—that is, with an opening extending longitudinally through it; and in one side is formed a longitudinal slot, *a*, upon the edge of which, on the body A', may be arranged a scale indicating a series of seconds or half-seconds in figures; but I prefer to dispense with such a scale, and use a fuse which has a graduated scale having second and half-second marks arranged in figures upon its surface, which figures will appear through the slot. When it is desired to communicate a flame to the charge in the shell or projectile, a knife or

other suitable device is inserted through the longitudinal slot *a*, perforating the covering of the fuse at the point desired, being guided by the scale either upon the fuse-case, whereby the flame is allowed to escape and communicate with the charge in the interior of the shell. By this means I avoid the necessity of cutting off the graduated fuse before it is applied to the fuse-case. The wall of the fuse-case at the front end, on the inside, is formed with one or more longitudinal grooves, *a'*, extending from the face of the head B down into the case to about where the front end of the fuse stops. The grooves *a'* are so formed as to receive and guide the spurs or legs or spurs and legs *c c* of a plunger, F, preventing the same from turning, while the base of said grooves forms a foundation for the cap to strike and cause the same to explode. The front plunger F, besides being formed with one or more spurs or legs, *c*, to receive percussion-caps, has attached to its body or portion *d*, in any suitable manner, a plate or spring, *e*, the end or ends of which plate or spring engage or enter a groove or slot, *f*, formed in the head B, by which means the plunger is retained in its proper position and prevents premature explosion, when the said fuse is charged and capped, during transportation, handling, &c. The spurs or legs *c* are formed or provided with steel or other hard-metal points, *g*, which are of a less diameter than the diameter of the percussion-caps, so that when the shell or projectile is fired the force of the blow is concentrated at one point upon the fulminate in the said percussion-cap or caps, whereby a greater certainty of explosion is secured. The body A of the fuse-case, near its rear end, is formed with a diametrical slot, G, extending from about the point where the rear end of the fuse terminates in the said fuse-case to within a short distance of the end, as designated by the letters *h i*. Within this slot G is arranged loosely a plunger, H, which, when placed in said slot, has its edges *j j* headed so as to prevent the said plunger from dropping out laterally. The body or head I of this plunger is formed or provided with one or more spurs or legs, *l l*, which are provided with steel or other hard-metal points, *m m*, of a diameter less than the internal

diameter of the percussion cap or caps, similar to the front plunger F, except that the front plunger communicates with the fuse, while the rear plunger communicates directly with the powder in the shell. Upon the body or head I of this plunger H is secured, in any suitable manner, a plate or springs, o, the end or ends of which rest in a groove or recess, e', or other suitable retainer, upon the end of the fuse-case, so as to retain the said plunger in its proper position and prevent premature explosion during transportation, handling, &c., by keeping the spurs or legs carrying the percussion-caps out of contact with the wall or stop against which it hits when the shell strikes. When a shell or projectile containing a fuse, as above described, is fired, the force of impact breaks the retaining plate or spring, or causes the same to yield and follow the receding front plunger down, until the percussion cap or caps upon the steel or hard-metal points g g of the legs c c strikes the base of the grooves, exploding the caps, the flame of which ignites the front end of the fuse, and when the fuse has burned to the perforation, the flame bursts forth and communicates with the powder in the shell. In case the flame has not reached the perforation in the fuse before the shell strikes, which may occur from too low elevation, the rear plunger H is thrown forward in the slot G by impact, the percussion-caps upon

the steel points m m strike against the end h of the slot b and explode the caps, which communicates the flame directly to the charge in the shell.

An important and essential feature of this fuse is that it can be charged upon issue, or at a moment's notice, it being well known that fuses which are two or three years old absorb moisture, and thereby become useless.

It should also be understood, by the peculiar construction of this fuse—that is, by the employment of the rear plunger—its function and certainty of execution are not interfered with when the shell strikes upon water, as it is, in fact, hermetically sealed.

Having thus described my invention, what I claim as new, and desire to secure by Letters Patent, is—

A fuse-case provided with the grooves a' a', in combination with the plunger F, having spurs or legs c c to receive percussion-caps, and provided with the retaining-spring e adapted to a groove or slot, f, in the fuse-case, all arranged to operate substantially as described.

To the above I have signed my name this 11th day of December, A. D. 1871.

ELLIS DRAKE.
